Primary Examiner — Susan Bennett Hattan*Assistant Examiner* — Lauren D McVey(74) *Attorney, Agent, or Firm* — McClure, Qualey & Rodack, LLP(57) **CLAIM**

The ornamental design for a printer, as shown and described.

DESCRIPTION

FIG. 1 is a top left front perspective view of a printer, showing our new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top right perspective view thereof.

The broken lines depict portions of the printer that form no part of the claimed design.

1 Claim, 6 Drawing Sheets(56)
